UNITED STATES PATENT OFFICE.

CHARLES E. DAILEY, SR., OF PITTSBURGH, PENNSYLVANIA.

LAMP-TURNING MECHANISM.

1,355,215.

Specification of Letters Patent. Patented Oct. 12, 1920.

Application filed December 30, 1918. Serial No. 268,834.

To all whom it may concern:

Be it known that I, CHARLES E. DAILEY, Sr., a citizen of the United States, residing at Pittsburgh, in the county of Allegheny

5 and State of Pennsylvania, have invented new and useful Improvements in Lamp-Turning Mechanism, of which the following is a specification.

This invention relates to mechanism for 10 turning lamps, and more particularly automobile lamps, and has for its primary object to provide mechanism whereby the lamps will automatically follow the contour of a road and are capable of being swung vertically for varying the travel of the rays of light.

An object of the invention is to provide two sets of mechanism acting independently of each other one manually operated and the 20 other automatically operated for swinging the head lamps in two directions.

Besides the above my invention is distinguished in the novel manner of tilting the lamps so that the rays of light thereof will 25 not effect the driver of an approaching car.

With these and other objects in view the invention will be better understood from the following detailed description taken in connection with the accompanying drawing 30 wherein:

Figure 1 is a side elevation of the device shown somewhat enlarged for the purpose of illustration.

Fig. 2 is an enlarged view of a portion of 35 the mechanism.

Fig. 3 is a detailed sectional view through a portion of the operating link.

Fig. 4 is a top plan view of the mechanism with one of the lamps removed.

40 Fig. 5 is a detailed sectional view through a portion of the lamp showing its pivotal connection.

Fig. 6 is a detailed perspective view of a portion of the operating mechanism.

45 Again referring to the drawings which illustrate my invention in one of its forms the numeral 1 designates the lamps of a pair of head lamps each having an inclined lens for restricting the direction of the travel of 50 the light rays. As clearly shown in Fig. 5 the lamp 1 has riveted thereto ears 2, each having a pivotal connection with a bracket

55 3. This bracket 3 is rigidly connected to a shaft 4 mounted for rotation in a frame 5 secured in any suitable manner to the frame of an automobile. The frame 5 is provided

with a projection 6 forming a bearing for a gear 7. This gear 7 has riveted thereto a plate 8 that in turn has a pivotal connection 9 with a link 10.

60 This link 10 is slotted and supports a pair of concave rollers 11 between which slidably moves an arcuate rod 12. This rod 12 is concentric with shaft 4 and is rigidly secured to ears 2 with a result that when movement 65 is given to the link 10 the lamp 1 will be tilted or rocked vertically owing to its pivotal connection with the bracket 3.

As far as I have proceeded it will be seen that the lamp 1 may have its light rays 70 thrown directly in front of the front wheels of the machine or elevated above the machine, as desired. For giving movement to the gear 7 I have shown one form of mechanism that has proved practical and which 75 is manually operated. This mechanism consists of a segmental gear 13 meshing with the gear 7. The shaft 14 of the gear 13 is keyed to a slotted lever 15, the slot 16 of which engages a pin 17 on an arm 18. The 80 arm 18 associated with each lamp, is rigidly connected to a horizontally disposed rotatably mounted shaft 19 passing transversely across the frame of the automobile. This shaft has projecting therefrom an arm 85 20 having a pivotal connection with any suitable form of link mechanism 21 that may be manually operated by a lever 22 within convenient reach of the driver of a machine.

90 Thus it will be seen that by manipulating the lever 22 the lamps through the medium of the heretofore mentioned devices may be swung vertically. The shaft 4 of each lamp has secured thereto an arm 23, these arms being connected by a pair of telescoping members 24, one of which carries a set screw 25 adapted to bind against the other for accommodating adjustment of the members or 100 their disconnection, so that both lamps may be actuated simultaneously in an automatic manner now to be described. One of the members 24 has connected thereto a substantially L shaped link 25^a connected to the turning mechanism 26 of the machine by 105 having a pivotal connection with a finger 27 projecting from the wheel spindle of the turning mechanism 26.

110 In use the lights or lamps 1 may both be tilted simultaneously by raising or lowering the links 10, this raising or lowering of the links causing corresponding movement of

the rods 12 and consequent tilting of the headlights. As the rods 12 are disposed concentric with shafts 4 of the headlights for the greater portion of their length, as 5 illustrated, and are slidably between the rollers 11 the headlights may be turned in either direction about their vertical axes and the rods 12 serve to guide and brace the lights during this turning movement.

10. Having described my invention, what I claim is:

1. In combination, a pair of headlights each mounted for vertical and horizontal swinging movements, an arcuate rod connected to each light, a link device including rollers supporting said rod, means for operating said link vertically for tilting the rod and the light connected thereto, and means for connecting said headlights to the steering mechanism of an automobile so as to be turned about their vertical axes in accordance with movement of said mechanism.

2. In combination, a pair of head lights each mounted for movement about a horizontal axis and about a vertical axis, arcu- 25

ate rods secured to the respective lamps and disposed concentric with the vertical axis of movement thereof, means for raising or lowering the rods to rock the lamps about their horizontal axes, said means slidably receiving the rods to permit free turning of the lamps about their vertical axes and to brace and guide the lamps during such movement, and means for connecting the lamps to the steering mechanism of an automobile so as to be turned thereby in accordance with movement of said mechanism.

3. In combination, a lamp mounted for movement about a horizontal axis and about a vertical axis, a link, means for operating 40 said link vertically, and an arcuate rod secured to said lamp and disposed concentric with the vertical axis of movement thereof, said rod being operable so as to tilt the lamp about its horizontal axis in accordance with 45 the operation of said link while slidably through the link to permit turning of the lamp about its vertical axis.

In testimony whereof I affix my signature.

CHARLES E. DAILEY, SR.
